4 Claims**ABSTRACT OF THE DISCLOSURE**

This invention is a simplified logic system for a high speed chain printer in which the columns are printed one at a time. The chain circulates in a direction opposite to the direction in which the columns are printed while an incremental encoder produces an output pulse each time a type font moves past a hammer. These pulses are counted and compared to the input data. Each time a column is printed, an extra pulse is coupled to the counter in order to account for the fact that a particular character arrives in printing position one count earlier for each successive column.

Background of the invention

This invention relates to a high speed impact printer and, more particularly, to a simplified logic system for a high speed impact chain printer that prints one column at a time.

Conveniently, in high speed chain printers, an incremental shaft position encoder is used for determining the position of the type font with respect to the print hammers. The encoder typically provides one pulse for each character of the font so that in one complete circulation of the font past the print line the encoder provides as many pulses as characters (i.e., 64 characters, 64 pulses). A binary counter counts these pulses and its output is compared with the input from a data source. When the output of the counter coincides with input data (which is encoded as a binary number), an output from the comparator causes a selected hammer to fire.

The position of the characters is synchronized usually with the first hammer, and a reset signal is generated at the end of each complete circulation to reset the counter. A count of one (1) may, therefore, indicate that the letter A is in printing position opposite the first hammer; a count of two (2), that the letter B is in printing position opposite this same first hammer and so on. However, owing to the fact that in a chain printer the character font advances along a line parallel to the print hammers, the same count does not indicate the same letter is in position with respect to the second and successive hammers.

Several logic systems have been proposed in the prior art for chain printers to account for the fact that with an incremental encoder a particular count indicates a particular character only with respect to a single column. Such prior art systems, while generally satisfactory, are relatively complex and expensive.

The logic of this invention is the provision of a logic system for character at a time chain printers which simply and inexpensively correlate an incremental encoder output with the column being printed.

Summary of the invention

Briefly, this invention contemplates a chain printer in which the chain circulates in a direction opposite to that in which the columns are printed, and a logic system utilizing an incremental encoder and a counter which cycles at a count equal to the number of characters of the font. One additional pulse is coupled to the counter each time

2

a hammer fires and the counter is not reset until a complete line has been printed. In this simple manner, the count in the character position code counter advances so that a particular character is in printing position for each successively selected hammer.

Brief description of the drawings

Having briefly described this invention, it will be described in greater detail along with other objects and advantages in the following detailed description of a preferred embodiment which may be best understood by reference in the accompanying drawing which forms a part of the instant specification and which is to be read in conjunction therewith and in which the sole figure is a block diagram of a chain printer employing one embodiment of the simplified logic system of this invention.

Description of the preferred embodiments

Referring now to the drawing, a motor 10 drives a print chain or belt 12 horizontally from right to left (in the direction of the arrow) past a line of solenoid actuated print hammers 14 in a manner known to those skilled in the art. See, for example, the copending application Ser. No. 509,501, filed Nov. 24, 1965 and assigned to the same assignee as this invention.

An incremental encoder is synchronously driven with the chain 12; it may comprise a metallic disc 16 with a number of slots equal in number to the type elements on chain 12 and a transducer 18 magnetically coupled with the disc. The transducer produces an output pulse each time a tooth passes the gap in the transducer. A second encoder 22 has a single slot; it generates a reset pulse each time the letter A is in printing position with respect to the left hand hammer. If desired, a single encoder may be employed for generating both character position pulses and the reset pulse in the manner shown in U.S. Patent No. 3,117,514.

The output of transducer 18 is coupled via an OR gate 24 to a position encoding counter 26, which is a binary counter whose maximum count is equal to the number of characters on the chain 12. The output of encoder 22, which is coupled to counter 26 via an AND gate 21, resets counter 26.

The output of the counter 26 is coupled to a comparator circuit 28 whose input is binary encoded input data from a suitable source 32 such as a buffer register, for example.

The output of the comparator 28 is coupled by AND gates 35 and amplifiers 36 to the operating coils of the solenoid operated print hammers 14 to the end that when the output of counter 26 matches the input from data source 32 a selected one of the hammers 14 fires.

The hammers 14 are selected sequentially by a second counter 34, starting with the left-hand hammer in the embodiment shown and proceeding to the right a column at a time. To this end, control logic circuit 37, which has one input coupled to the output of comparator 28, produces an output pulse each time a hammer fires; a counter 34 counts these pulses and enables sequentially each of the AND gates 35.

In addition, control circuit 37 has an input from the data source 32 and produces output pulse or pulses in response to certain input data such as, for example, when a column is to be skipped.

The output of control circuit 37 is coupled via OR gate 24 to the position counter 26 also so that the count therein advances one count each time a hammer fires or a column is skipped. In this manner, the logic system of this invention accounts for the fact that as the hammers are selected from left to right (for example) with the chain circulating in the opposite direction, a particular character arrives in a printing position one count earlier for each hammer selected.

An output from counter 34 enables gate 21 only while the first hammer 14 of the print line is selected, thereby preventing counter 26 from being reset until the last column has printed. Thusly, the count from control circuit 37 is cumulative during the printing of a single line.

In operation, a reset pulse from encoder 22 initially resets counter 26 and an output from counter 34 enables the gate 35 associated with the left hand hammer 14, for example. Counter 26 counts the pulses from transducer 18. When its output matches the binary encoded input 10 data from source 32, an output from comparator 28 is coupled with the left-hand hammer 14 via its enabled gate 36, firing this first hammer.

In response to the output from comparator 28, control circuit 37 produces an output which advances both 15 counter 34 and counter 26 one count. At the same time, gate 21 is disenabled, preventing the resetting of counter 26 until a complete line has been printed. Thusly, the count in counter 26 corresponding to each letter of the 20 font advances one count to account for the fact that each letter arrives at the second hammer one count earlier. When an entire line has been printed, gate 21 is again enabled, the counter reset by a pulse from encoder 22, and the operation is repeated.

Thus, it will be appreciated that the object of this 25 invention has been accomplished. By simply advancing the position counter one count for each printed (or skipped) column, the code in the position is maintained in correct correspondence with the column being printed.

It will be understood that certain features and sub-combinations are of utility and may be employed without reference to other features and subcombinations. This is contemplated by and is within the scope of the claims. It is further obvious that various changes may be made in details within the scope of the claims without departing 30 from the spirit of the invention. It is, therefore, to be understood that this invention is not to be limited to the specific details shown and described.

What is claimed is:

1. In an impact printer in which a type font moves 40 parallel to a line of print hammers in one direction and in which the character columns are printed one-at-a-time progressing in a direction opposite the direction of type font movement, a logic system comprising in combination:

first means for producing a pulse each time the font moves a pre-determined distance,
a counter having an input and an output,

said counter recycling at a predetermined count which is a function of the number of characters in said font, means for coupling the output pulses from said first means to the input of said counter to advance said counter,

a comparator having at least two inputs and an output, means for coupling the output of said counter to one input of said comparator,

a source of information, means for coupling said source of information to another input of said comparator,

said comparator producing an output signal when there is a comparison between its input signals, means for selecting each one of the print hammers sequentially,

means responsive to the output signal of said comparator for firing a selected one of said print hammers, and

means for coupling an input pulse to said counter to advance said counter one count each time a selected hammer is fired or a column is skipped.

2. A logic system for an impact printer as in claim 1 further including:

second means for generating a reset pulse each time said font completes one circulation, means for coupling said reset pulse to said counter to reset said counter, and said coupling means including means for blocking said reset pulse until a full line has been printed.

3. A logic system for an impact printer as in claim 2 wherein said counter recycles upon reaching a count equal to the number of type elements on said font.

4. A logic system for an impact printer as in claim 3 wherein said type font is mounted on a flexible belt.
